UNITED STATES PATENT OFFICE.

BURT A. PETERSON, OF ROCKFORD, ILLINOIS, ASSIGNOR TO HOWARD D. COLMAN, LUTHER L. MILLER, AND HARRY A. SEVERSON, COPARTNERS DOING BUSINESS AS BARBER-COLMAN COMPANY, OF ROCKFORD, ILLINOIS.

DOFFER.

1,117,437.

Specification of Letters Patent. Patented Nov. 17, 1914.

Application filed January 6, 1912. Serial No. 669,764.

To all whom it may concern:

Be it known that I, BURT A. PETERSON, a citizen of the United States, residing at Rockford, in the county of Winnebago and 5 State of Illinois, have invented certain new and useful Improvements in Doffers, of which the following is a specification.

This invention refers to portable machines for doffing ring spinning frames.

- 10 When a spinning frame is stopped, preparatory to doffing, the travelers come to rest at various points upon the spinning rings, with the yarn extending up from each traveler, along the bobbin, to the thread 15 guide or "pig-tail" directly above the bobbin. The thread guides are then swung up and back so as to be out of the way during the doffing operation. If the yarn extends up or across the forward side of the bobbin, 20 the yarn may not be able to slip off the bobbin so as to extend directly from the traveler to the thread-guide when the latter is thrown back, but on the contrary the yarn may extend from the traveler up or across 25 the bobbin, and then to the thread-guide. When the doffing device is moved downward over a bobbin whose thread is arranged as last described, the doffing device will push the thread down to the lower part of the 30 bobbin. Upon the upward movement of the doffing device and the bobbin, a few wraps of the yarn will slip off the bobbin onto the spindle as shown in Figure 14 of the drawings of Patent No. 983,858, issued February 35 7, 1911, upon an application filed by Howard D. Colman and myself. In this position, the yarn extends from the drawing rolls, across the spindle, to the traveler, and thence to the spindle. When the empty 40 bobbin is dropped onto the spindle the lower end of said bobbin will press against both strands (the strand running from the drawing rolls to the traveler, and the strand running from the traveler to the spindle) and 45 break the thread at the traveler.

The object of this invention is to provide means for dislodging any threads that fouled on the bobbins when the thread-guides were thrown back, in order to prevent breakage of the threads in the operation of placing empty bobbins on the spindles.

In the accompanying drawings, Fig. 1 is a fragmental elevation of the leading or ad-

vancing side of a doffer embodying my invention. Fig. 2 is a fragmental rear elevation. Figs. 3, 4 and 5 are fragmental top plan views in a series, showing successive steps in the operation of placing a thread in safe position for bobbin-donning. 55

In the drawings, *a* denotes a bobbin which has just been lifted from a spindle (not shown), and *b c d e* designate bobbins on the spinning frame. The ring rail is shown at *f*, *g* being spinning rings on said rail, and *h* being travelers slidably mounted on the rings in the usual way. 60

While the doffer may be of any preferred construction, I have herein illustrated the invention as applied to a doffer of the type 70 disclosed in said Patent No. 983,858. Using the same reference numbers as are applied to corresponding parts in said patent, 39 is the main shaft mounted in the doffer framework; 40 is the actuating crank fixed to the 75 forward end of said shaft; 41 is a cam disk fixed to the rear end of the shaft; 25 is a slide frame mounted on guides 31 and arranged to be horizontally reciprocated by the cam disk 41; 36 is a slide plate mounted 80 between vertical grooved guides 37 (Fig. 3); 22 is a doffing device fixed on the slide plate 36; 23 is a donning device fixed on the slide frame 25; and 38 is a channel bar fixed to the slide plate 36 and engaged by a roller 85 stud 44 on the cam disk 41, said cam disk imparting to the doffing device 22 a downward movement over a full bobbin, then a rising movement to lift the bobbin, then a horizontal movement to position the doffing 90 device over the next bobbin, and then a downward movement upon the last mentioned bobbin, such downward movement carrying the previously lifted bobbin against a stop 102 whereby said bobbin is detained 95 as the doffing device descends and thus discharged from said device. The cam disk also imparts to the donning device 23 reciprocating movement in a horizontal direction in the vertical plane of the spindles. 100

In Fig. 1 the doffing machine is to be understood as traveling toward the observer, and in Fig. 2 as moving to the left.

The threads leading from the thread-guides to bobbins *b*, *c* and *e* are in proper 105 position for doffing and donning, said threads extending upwardly and rearwardly from the travelers to the thread-guides.

The traveler for bobbin *d* is shown as at one side of the bobbin, and the thread as extending to the other side of the bobbin and thence to the thread-guide.

5 The means for moving out of the way of the empty bobbins any threads that might otherwise be contacted and broken by said bobbins consists, in the illustrative embodiment herein shown, of an arm 104 pivoted 10 at 105 to the horizontally moving slide frame 25. On the upper end of the arm 104 is a horizontal member 106 having oppositely inclined surfaces 107, 108 thereon. The thread-moving arm 104 operates on a 15 bobbin in advance of the bobbin being doffed; in this embodiment, upon the second bobbin ahead of the bobbin being doffed. As the doffing device descends upon a bobbin, the channel bar 38 (which is attached 20 to the slide plate 36 that carries the doffing device) contacts the arm 104 and causes it to swing rearwardly, as indicated in dotted lines in Fig. 1. When the channel bar rises, a spring 109 restores the arm 104 to its 25 normal position, such position being determined by contact of the arm with a stop shoulder 110 on the slide frame 25.

Referring to Figs. 1 and 3 which illustrate the bobbin *d*: When the arm 104 swings rearwardly, the surface 108 contacts the thread at a point above the bobbin, and "cams" or pushes said thread aside. After the surface 108 has passed the thread, the latter springs back so as to lie in front of 35 the surface 107, as represented in Fig. 4. Upon the return movement of the arm, the surface 107 moves the thread forward until the latter is clear of the bobbin whereupon the thread slides off said inclined surface 40 107 to the side of the bobbin at which the traveler is standing, and drops into the vertical plane of the traveler and thread-guide. In this position, the thread will not be broken when the empty bobbin is placed 45 upon the spindle. It will be seen that the arm 104, operating as it does in advance of the doffing device, insures that all of the threads shall be in proper position for the doffing operation.

50 As hereinbefore stated, when the spinning frame is prepared for doffing, the travelers and threads stand in various positions. Fig. 8 illustrates one of the most troublesome

positions. In some instances the thread may stand in such position that the surface 55 108 will press the thread rearwardly and cause the traveler to swing around toward the rear, so that the thread will be in safe position for doffing.

I claim as my invention:

60 1. In a doffer, a doffer framework, and a member at the rear side of the framework and movable toward and away from said framework, said member being inclined to push a thread forward and sidewise.

65 2. In a portable doffer for ring spinning frames wherein a thread extending from the drawing rolls to a traveler may become fouled on a bobbin, a framework adapted to travel along the front of the spinning frame, 70 a doffing device carried by the framework, an arm attached to the framework for lifting a fouled thread off the bobbin, and means for operating said arm in advance of the operation of the doffing device.

75 3. In a doffer, a doffer framework, a bobbin-doffing device carried by the framework, and means for engaging a thread and moving it toward the doffer framework, said means permitting the thread to escape when 80 clear of the bobbin.

85 4. In a doffer, a doffer framework, an upwardly extending arm pivoted at its lower end upon the rear side of the framework, a member on the upper end of said arm having two oppositely inclined surfaces each adapted to deflect a fouled thread, and means for swinging said arm.

90 5. In a doffer, a doffer framework, a horizontally reciprocable slide frame in said framework, a vertically reciprocable slide on said slide frame, a doffing device on said slide frame, an arm pivoted at its lower portion on said slide frame, means to swing the arm rearwardly as the slide descends, means 95 to restore the arm as the slide ascends, and a member carried by the upper portion of said arm, said member having two oppositely inclined edges adapted to deflect a fouled thread.

100 In testimony whereof I affix my signature in the presence of two witnesses.

BURT A. PETERSON.
